UNITED STATES PATENT OFFICE.

VIRGIL P. WARREN, OF ATLANTA, GEORGIA.

REFRIGERATOR WALL.

Application filed September 24, 1924. Serial No. 739,727.

This invention relates to a wall construction, particularly designed for use in refrigerators. As is well known, provision must be made for expansion and contraction of refrigerator walls and it is essential that there be no leakage of air between the joints in the walls. I have devised an improved form of joint which will effectually prevent such leakage, the joint having two sliding surfaces which effectually prevent leakage.

Referring to the drawings, Fig. 1 is a perspective view of a portion of a refrigerator, the door of the same being shown in open position to show how the interior appears with my improved walls;

Figs. 2 and 3 are cross-sections through the refrigerator walls, showing the same in fully and partially expanded position, respectively.

The walls are made up of a plurality of relatively narrow strips 1 suitably secured to the frame of the refrigerator to permit relative displacement thereon. Each side of the strip is cut back along one edge to form a tongue 2 and an angular extension 3 at the end of the tongue, the extensions being reversely arranged and of such length that a sliding fit is had with the adjacent tongue of the next strip when the said strips are laid on the refrigerator frame. The tongues overlap but are spaced from each other. Each joint therefore has two extensions co-operating with the flat surfaces of the

tongues, thus providing a double seal against leakage of air around the joint. The extensions also cooperate to prevent separation of the joint as will be readily appreciated by reference to the drawings.

The interior and exterior of the refrigerator are provided with the improved wall, the walls being spaced apart and filled with suitable insulating material not shown.

What I claim is:

A wall including framework, siding strips secured to said framework and having similar slidably connected interlocking joints formed by providing diagonally opposite edges of each strip with rabbets of the same width and depth and grooving the face of each rabbet parallel to the sides of said strip similarly to form a lateral tongue on each rabbeted edge of said strip, the groove so formed being substantially wider than the width of said tongue, the strips being secured to said framework with the tongues of each strip in the grooves of the adjacent strips and in lateral contact with the tongues of said adjacent strips to allow each tongue to slide laterally, when the strips expand, in contact with the bottom of the groove in the adjacent strip, and thereby provide a double seal against air leakage around the joint.

In testimony whereof I affix my signature.

VIRGIL P. WARREN.
